ULTRA-VIOLET LAMP OR SIMILAR ARTICLE

Gustav Hubert, San Gabriel, Calif., assignor to Ultra-Violet Products, Inc., San Gabriel, Calif., a corporation of California

Filed Feb. 8, 1965, Ser. No. 83,723

Term of patent 14 years

(Cl. D48—20)

FIG. 1 is a front perspective view of an ultra-violet lamp or similar article, showing my new design;
FIG. 2 is a side elevational view thereof;
FIG. 3 is a top plan view thereof;
FIG. 4 is a bottom plan view thereof; and
FIG. 5 is a back elevational view thereof.
I claim:

The ornamental design for an ultra-violet lamp or similar article, substantially as shown.
